UNITED STATES PATENT OFFICE.

HENRY E. BORGER, OF NEWARK, NEW JERSEY, ASSIGNOR TO SPLITDORF ELECTRICAL COMPANY, OF NEWARK, NEW JERSEY.

AUTOMATIC CUT-OUT FOR ELECTRIC GENERATORS.

1,308,275.

Specification of Letters Patent.

Patented July 1, 1919.

Application filed August 24, 1917. Serial No. 187,944.

To all whom it may concern:

Be it known that I, HENRY E. BORGER, a citizen of the United States, residing at Newark, in the county of Essex and State of New Jersey, have invented a new and useful Improvement in Automatic Cut-Outs for Electric Generators, of which the following is a specification.

In the use of electric generators for automotive vehicles it is general practice to use electromagnetic devices for switching the generator on and off the storage battery which is customarily used on such vehicles for the purpose of operating starting motors 15 and lights and other accessories.

It is the object of my invention to provide a mechanical device for controlling the working circuit of such a generator, which device will be much simpler and less expensive than the electromagnetic switching 20 arrangement now in general use.

While providing a simple and inexpensive device for this work, it is another object of my invention to provide a device that is responsive to an ever-present and electrically unchanging force whereby the control of the generator working circuit is rendered positive and accurate.

Another object of my invention is to provide an automatic cutout which is easy to install and readily gotten at for repairs or renewals in case of necessity.

These and other objects will be apparent to one skilled in the art after a study of the drawings taken in connection with the annexed specification.

In the drawing, Figure 1 is a side view of my generator with the cover for protecting the automatic cut out parts removed.

Fig. 2 is a left hand end view of Fig. 1.

Fig. 3 is a top plan view of Fig. 1.

Fig. 4 is a sectional view of the cover used to protect the commutator end and cutout mechanism.

Fig. 5 is an enlarged view of the governor forming a part of the automatic cutout.

Fig. 6 is a diagrammatic arrangement of one type of work circuit used in connection with the generator.

Referring now particularly to the details, 1 is a generator having an armature whose commutator is shown at 2. In Fig. 1 a brush 3 is shown resting on the commutator. One

end of the armature shaft projects at 4 for the purpose of mounting a driving pulley or gear thereon. A commutator end bearing head 5 is held to the body of the generator by bolts 6 which pass through the interior framework and engage bosses (not shown) on the interior of head 5. The other end of the generator armature shaft projects through the head at 7. The end 7 is bored out at 8 forming a hollow chamber. A pin 9 is mounted in the hollow end 8 substantially at right angles to the shaft, spacing collars 11 being used for separating a weight member in the form of a ring 12. The pin 9 is flattened off at 13 to form a cam. The end of pin 9 is preferably slotted at 14 so that the pin may be set with the flat or cam surface 13 pointed toward the open end of the hollow portion 8. A pin or rivet 10 is used to hold the ring member 12 in position on the pin 9. Supported in the hollow end 8 is a thrust member 15 whose end is preferably slightly rounded at 16 for a purpose which will be hereinafter described. Mounted on the commutator head 5 is a bracket 17 upon which is pivotally mounted a movable member 18 having two arms 19 and 20. In the end of arm 19 is fastened a wearing piece 21 preferably of fiber or some other material. Associated with the movable member 18 is a spring 22 of any suitable type, but shown in Fig. 1 as of the bifurcated type, one end 85 of which rests against the bracket 17 and the other against a portion of the arm 20. One part of the arm 20 carries a contact 23. Mounted in a relatively fixed position on the bracket 17 but insulated therefrom is a 90 spring member 24 which carries contact 25 that is adapted to co-operate with the contact 23 on the arm 20 of the movable member 18. The function of spring 22 is to normally keep the contacts 23 and 25 separate at the same time it carries the arm 19 of the member 18 in such position that the wearing piece 21 pushes against the end of thrust member 15 so that the cam 13 and ring 12 are normally held in a position shown in 100 Fig. 1 when the generator is not in operation.

It will be seen that the movable member 18 is used for the double purpose of controlling the working circuit of the generator 105 through the contacts 23 and 25 and to return

the governor mechanism to its normal inoperative position, thus eliminating the use of any further resilient member at the governor itself for this latter purpose.

- 5 A cover 26 is adapted to fit over the commutator head 5 inclosing the commutator, governor and cutout springs. The cover may be held to the head 5 by screws engaging the holes 27.
- 10 In Fig. 6 the generator 1 is shown as having two main brushes 3 and 28 and a third or regulating brush 29 which is connected to one end of the field winding 30, the other end of which is connected to the 15 main brush 3. While the brush 29 is shown in a certain position in Fig. 6 it is to be understood that this position is adjustable for the purpose of getting the required output at the desired speed of the generator.
- 20 The main brush 3 is connected internally to the binding post 31 and the brush 28 to the spring member 24. Since the movable member 18 is connected to the frame of the generator which is ground, the circuit from the 25 generator will be completed through the battery B as soon as the contacts 23 and 25 are closed as above described. H illustrates a head lamp and S side lamp, both being controlled by separate switches 32 and 33.
- 30 It will be understood that the parts of the automatic cutout are adjusted so that the working circuit of the generator will not be closed until the voltage has reached a value slightly above that of the battery B. When 35 the voltage of the generator has reached this predetermined point the weight member 12 is operated by centrifugal force to turn the member 12 at right angles to the shaft 7. In doing this the pin 9 and cam 13 are 40 turned, which operation pushes the thrust member 15 outward against the wearing piece 21 thereby operating the movable arm 18 to close the contacts 23 and 25. It will be also seen that the member 12 is self-regulating as to the amount which it pushes the 45 thrust member 15 outward. That is to say, the member 12 under the effect of centrifugal force will move to a position so that the pressure of the contacts 23 and 25 never 50 exceed a given amount no matter how fast the generator is run. This gives a definite minimum pressure to the contacts and a definite minimum amount of wear between the 55 wearing piece 21 and the thrust member 15 which is a very important feature of my invention.
- The generator shown in the various views is particularly adaptable for charging a battery and lighting lamps on a motorcycle 60 but it is also applicable to any other moving vehicles and I do not wish to be limited to any particular application.
- 65 It will be clearly apparent that numerous changes and alterations may be made in the details of various parts of my invention

without departing from the spirit of the invention or the scope of the appended claims.

Having thus described my invention what I claim is:—

70 1. In an automatic cutout for electrical generators, the combination of a shaft having a hollow end, a pin extending through the hollow end of said shaft, a thrust member seated in said hollow shaft end and adapted to be acted on by said pin, a circular member supported on said shaft by said pin and adapted to be acted on by centrifugal force as said shaft rotates, a fixed spring member carrying a contact and a movable member carrying a contact and adapted to be operated by said thrust member whereby the movement of said circular member operates said contacts.

75 2. In an automatic cutout for electrical generators, the combination of a shaft having a hollow end, a pin extending through the hollow end of said shaft, said pin having a flat portion normally facing toward the end of said shaft, a thrust member carried in the hollow end of the shaft and normally resting against the flat portion of said pin, an annular ring member supported on said shaft by said pin and adapted to be acted on by centrifugal force to turn 80 said pin against the thrust member as said shaft rotates, a fixed spring contact member and a movable contact member adapted to be acted on by said thrust member to close an electrical circuit.

85 3. In an automatic cutout for electrical generators, the combination of a shaft having a hollow end, a pin extending through the hollow end of said shaft, a thrust member seated in said hollow shaft end and 90 adapted to be acted on by said pin, a circular member supported on said shaft by said pin and adapted to be acted on by centrifugal force as said shaft rotates, a fixed spring member carrying a contact and a movable member carrying a contact and means acting on the last mentioned member to normally hold said contacts in open position and to hold the thrust member, pin and circular member also in normal position.

95 4. In an automatic cutout for electrical generators, the combination of a shaft having a hollow end, a pin extending through the hollow end of said shaft, said pin having a flat portion normally facing toward the end of said shaft, a thrust member carried in the hollow end of the shaft and normally resting against the flat portion of said pin, an annular ring member supported on said shaft by said pin and adapted to 100 be acted on by centrifugal force to turn said pin against the thrust member as said shaft rotates, a relatively fixed member carrying a contact, an L shaped movable member carrying a co-operating contact on one 105

of its arms and a wearing piece on the other arm adapted to be engaged by said thrust member, means acting on said movable member to resist the action of the thrust member whereby the thrust member is returned to its normal position when the electrical generator is stopped or its speed reduced to a predetermined value and the said contacts are separated.

10. 5. In an automatic cutout for electrical generators, the combination of a governor having the following instrumentalities, a hollow shaft end, a pin extending through said hollow shaft end and having a cam portion in the hollow shaft, a ring mounted on the ends of the pin and adapted to be acted on by centrifugal force to turn the pin, a thrust member seated in the hollow shaft and adapted to be acted on by said cam portion; and a relatively fixed member carrying a contact mounted on the generator, and a second member carrying a contact adapted to coöperate with the first, said second member being movably mounted on the generator in a position to be acted on by said governor for the purpose described.

6. In an automatic cutout for electrical generators, the combination of a governor having the following instrumentalities, a hollow shaft end, a pin extending through said hollow shaft end and having a cam portion in the hollow shaft, a ring mounted on the ends of the pin and adapted to be acted on by centrifugal force to turn the pin, a thrust member seated in the hollow shaft and adapted to be acted on by said cam portion; and a relatively fixed member carrying a contact mounted on the generator, and a second member carrying a contact adapted to coöperate with the first, said second member being movably mounted on the generator in a position to be acted on by said governor, and means acting on the second member to return the governor to normal position and open said contacts.

7. In an automatic cutout for electrical generators, the combination of a relatively fixed member carrying a contact, a movable member carrying a contact adapted to operate with the first contact to control an

electrical circuit, and a governor having a thrust member mounted in a hollow shaft end and adapted to act on the movable member and a ring member mounted on the shaft end and adapted to be actuated by centrifugal force to move the thrust member, said ring member being so mounted that it will move the thrust member only a predetermined distance as and for the purpose described.

8. In an automatic cutout for electrical generators, the combination of a relatively fixed member carrying a contact, a movable member carrying a contact adapted to co-operate with the first contact to control an electrical circuit, and a governor having a thrust member mounted in a hollow shaft end and adapted to act on the movable member and a ring member mounted on the shaft end and adapted to be actuated by centrifugal force to move the thrust member, said ring member being so mounted that it will move the thrust member only a predetermined distance and means acting on the movable contact member to return the governor parts to their normal position and open the said contacts when the speed falls below a predetermined value.

9. In an automatic cutout for electrical generators, the combination of a governor having the following instrumentalities, a hollow shaft end, a pin extending through said hollow shaft end and having a cam portion in the hollow shaft, a ring mounted on the ends of the pin and adapted to be acted on by centrifugal force to turn the pin, a thrust member seated in the hollow shaft and adapted to be acted on by said cam portion; and a lever pivoted on a support attached to the generator, said lever having two arms, one extending into the path of movement of said governor thrust member, the other carrying a contact; and a relatively fixed but flexible member carrying a contact mounted on said support, said contacts being adapted to control an electrical circuit as the pivoted lever is moved by said governor.

In witness whereof, I affix my signature.
HENRY E. BÖRGER.
